UNITED STATES PATENT OFFICE

105,627

DESIGN FOR A DISPENSER

Walter W. White, Englewood, N. J., and John Vassos, Norwalk, Conn., assignors, by mesne assignments, to Emerson Drug Company, Baltimore, Md., a corporation of Maryland

Application June 5, 1937, Serial No. 69,700

Term of patent 14 years

To all whom it may concern:

Be it known that we, Walter W. White and John Vassos, citizens of the United States and residents, respectively, of Englewood, in the county of Bergen and State of New Jersey, and of Norwalk, in the county of Fairfield and State of Connecticut, have invented a new, original, and ornamental Design for a Dispenser, of which the following is a specification, reference being had to the accompanying drawings, forming part thereof.

We claim:

The ornamental design for a dispenser, as shown.

WALTER W. WHITE.
JOHN VASSOS.
